UNITED STATES PATENT OFFICE

103,077

DESIGN FOR A PANORAMA DOLLY

Ralph Gordon Fear, Los Angeles, Calif.

Application February 15, 1936, Serial No. 61,193

Term of patent 7 years

To all whom it may concern:

Be it known that I, Ralph Gordon Fear, a citizen of the United States, residing at #449 North Kings Road, in the city of Los Angeles, in the county of Los Angeles and State of California, have invented a new, original, and ornamental Design for Panorama Dolly, of which the following is a specification, reference being had to the accompanying drawings, forming part thereof.

Figure 1 is a side elevation in perspective of a panorama dolly showing my new design, and

Figure 2 is a front elevation in perspective of a panorama dolly showing my new design.

What I claim:—

The ornamental design for a panorama dolly, as shown.

RALPH GORDON FEAR.
